UNITED STATES PATENT OFFICE.

JOHN N. CAREY, OF OAKMONT, PENNSYLVANIA.

CHARGING DEVICE.

Application filed April 13, 1921. Serial No. 460,941.

To all whom it may concern:

Be it known that I, JOHN N. CAREY, a citizen of the United States, and resident of Oakmont, in the county of Allegheny 5 and State of Pennsylvania, have invented a new and useful Improvement in Charging Devices; and I do hereby declare the following to be a full, clear, and exact description thereof.

10 My invention relates to a charging device, and while not limited to any specific use, it is particularly adapted for use in connection with the charging of a batch into a tank furnace for melting glass.

15 One of the main objects of my invention is to provide a device of this character which is simple and durable in construction, and in which the pusher-plate (where a pusher-plate is employed) is so arranged that 20 after the batch has been pushed into the furnace the pusher-plate, in withdrawing, is elevated so as not to move in contact with the top of the molten glass, thereby saving the wear on the plate, and at the same time 25 preventing the accumulation of thick or hardened glass around the charging opening.

To these ends my invention comprises the novel features hereinafter set forth and claimed.

30 In the accompanying drawing, Fig. 1 is a longitudinal elevation of my improved charging device partly in section, the position of the charging device when advanced into the furnace being shown in dotted lines; 35 Fig. 2 is an enlarged horizontal section broken away; Fig. 3 is a like view showing the pushing-plate in position in the furnace to advance the batch; Fig. 4 is an enlarged section on the line 4—4, Fig. 1; Fig. 5 is a 40 section on the line 5—5, Fig. 2, and Fig. 6 shows a modified form of my invention.

In the drawings the numeral 2 designates a portion of a suitable tank-furnace for melting glass, having the charging opening 3 controlled by the door 4. The front cross-wall 5 juts out beyond the body of the furnace and it is over this wall that the pusher-plate passes after the material has been discharged into the furnace, as will more 45 fully hereinafter appear.

The numeral 6 designates the frame-work which may be built up of channels and angle-bars in any suitable manner. A track 7 is formed by the angle-bars 8 and said 50 track forms the support for the wheels 9

on the main carriage 10. The sides 11 of the main carriage 10 have the grooves 12 formed therein which form seats for the bars 13 which are secured in place on said carriage by the bolts 14. The outer ends 60 of the bars 13 are pivotally connected, as at 15, to the lugs 16 on the pusher-plate 17.

A cylinder 18 is provided whose plunger 19 is connected at its forward end by the pin 20 to the supplemental carriage 24. 65

To provide against lateral movement of the carriage 10, said carriage is provided with the rollers 21 which engage the flanges 22 of the channels 23 secured to the frame 6.

The supplemental carriage 24 is mounted 70 on the carriage 10 and for this purpose brackets 25 on the carriage 10 are provided, the shelves 26 of said brackets forming the tracks for the wheels 27 of said supplemental carriage 24. To prevent the vertical movement of said carriage, retaining plates 28 are provided which are secured to the tops 29 of the brackets 25. The supplemental carriage 24 has the opening 30 for the passage of the plunger 19, said supplemental carriage 24, as will hereafter appear, having a movement independent of the movement of said carriage 10. 75

A compensating arm 31 is pivotally mounted by the bolt 32 on the supplemental 80 carriage 24, and at the opposite ends of said compensating arm are secured the clevises 33 to which the bars 34 are pivotally connected by the pins 35. The outer ends of the bars 34 are pivotally connected by 85 the pins 36 to the upper end of the lugs 16 of the pusher-plate 17.

A bell-crank 37 made up of separate pieces 38 secured at their upper ends by the pin 39 and at their lower ends by the pin 90 37^a. This bell-crank 37 is pivotally mounted by the pin 40 on the carriage 10, as clearly shown in Fig. 5. A link 41 mounted on the pin 39 is connected by the pin 42 to the supplemental carriage 24. Mounted on the pin 37^a at the lower end of the bell-crank 95 37 is the roller 43 which is adapted to travel on the rail 44, said rail at the forward end having the downwardly curved portion 45.

Slots 46 and 47 formed in the carriages 105 24 and 10, respectively, make provision for the play or movement of the bell-crank 37, as will more fully hereinafter appear.

A lug 48 on the supplemental carriage 24 is adapted to engage a stop 49 on the car- 110

riage 10 to control the forward movement of said supplemental carriage, and a stop 49^a controls the rearward movement.

At the forward end of the carriage 10 is the flange 50 through which the bolt 51 passes, said bolt being secured at its inner end to the supplemental carriage 24. This bolt 51 carries the springs 52 and 53 which tend to take up any shock in the movement 10 of the carriage 24.

The rails 54 are provided on the frame 6 for the travel of the dump-car 55 containing the batch. This dump-car may be of any suitable construction and is moved back 15 and forth by the endless cable 56 which is driven by the motor 58.

Supported on the front wall 5 of the furnace is the plate 59 to which the shield 60 is connected by the angle 61, said shield 20 having openings formed therein for the passage of the bars 13 and 34.

When my improved charging device is in operation the batch contained in the car 55 is deposited by dumping the car into the 25 opening 3 of the furnace, the batch forming in a pile at this point. To advance the batch and distribute it properly in the furnace is the purpose of the pusher-plate 17, and during the discharge of the batch from the car 30 the pusher-plate is withdrawn in the position indicated in full lines, Figs. 1 and 2, the end of the plate being elevated above the top of the furnace wall 5 and the plate 59 so as not to be worn by moving back and 35 forth in contact with said wall or plate.

When the batch has been charged into the furnace the motive fluid is admitted to the cylinder 18 and the plunger 19 is advanced, moving the carriage 10 at the same time, 40 due to the bell-crank 37 being secured to the carriage 10 and connected by the link 41 to the supplemental carriage 24. As the carriage advances the bars 13 are advanced and with them the pusher-plate, until said 45 pusher-plate reaches the position indicated in dotted lines, Fig. 2. At this point the roller 43 of the bell-crank 37 has reached the curved portion 45 of the rail 44, and the further movement of the carriage 10 permits said roller to drop down over the 50 curved portion 45 of the rail 44 to the position indicated in full lines, Fig. 3. This allows the upper end of the bell-crank to advance and said bell-crank being connected by the link 41 to the supplemental carriage 24, said carriage is advanced by the dropping of the roller 43 from the rail 44, and said carriage takes the position indicated in 55 Fig. 3, engaging the stop 49. By this forward movement of the supplemental carriage 60 24 the compensating arm 31 is advanced, and with it the bars 34 which operate to tilt the pusher-plate 17 into a vertical position, as indicated in Fig. 3, with its lower half projecting below the front-wall 5 of

the furnace. The forward movement of the supplemental carriage 24 is limited by the lug 48 coming into engagement with the stop 49 and the further advance of the carriage 10 moves the pusher-plate forward into the 70 furnace and the batch is advanced as indicated in dotted lines, Fig. 1. When the batch has been properly advanced the cylinder 18 is reversed and the plunger 19 withdrawn. As the carriage 24 withdraws it 75 comes in contact with the stop 49^a on the carriage 10. During this movement of the carriage 24 the bars 34 are withdrawn and the pusher is tilted back into an inclined position so that its lower or scraping edge 80 is lifted from the molten glass in the tank, as shown in dotted lines Fig. 1, and as both carriages withdraw said pusher is withdrawn without any scraping action, being entirely free from the surface of the molten 85 glass. In this way the wear on the pusher-plate is reduced, and furthermore the pusher-plate, being free from contact with the molten glass, does not drag back with it toward the charging opening of the 90 furnace the top or scum of the glass, and collect it there where it hardens and prevents the proper charging of the furnace. The pusher-plate is tilted to such an extent that when it reaches the front wall 5 it is elevated above the said wall so as not to be 95 in contact therewith or with the plate 59, thereby saving further wear on said pusher-plate.

The compensating arm 31 allows for the 100 proper play of the bars 34 and relieves any undue strain.

In Fig. 6 I have shown my invention as applied to charging apparatus in which the batch is carried in a scoop which is moved 105 into the furnace and then tilted. The scoop 62 has the bars 63 and 64 pivoted at 65 and 66, respectively, and said bars correspond to and are operated in the same manner as the bars 13 and 34 to tilt said scoop. 110

What I claim is:

1. In a charging device, the combination of a carriage, means for advancing and withdrawing the same, a supplemental carriage on said first-named carriage, a forwardly tilttable member, connections between said member and said first-named carriage and between said member and said supplemental carriage, and automatic means for moving said supplemental carriage relatively to said first-named carriage whereby by movement of said supplemental carriage the tilttable member is operated. 115

2. In a charging device, the combination of a carriage, means for advancing and 120 withdrawing the same, a supplemental carriage mounted on said first-named carriage and relatively movable with reference thereto, a forwardly tilttable member, bars on said first-named carriage having pivotal 125

- connection with said member, bars on said supplemental carriage having pivotal connection with said member, and automatic means carried by said first-named carriage 5 for advancing and withdrawing said supplemental carriage relative to said first-named carriage whereby by movement of said supplemental carriage the tiltable member is operated.
- 10 3. In a charging device, the combination of a carriage, means for advancing and withdrawing the same, a supplemental carriage mounted on said first-named carriage and movable with relation thereto, a forwardly tiltable member, bars on said first-named carriage, pivotally connected to said member, bars on said supplemental carriage pivotally connected to said member, and a gravity operated member on said first-named carriage connected to said supplemental carriage, whereby said gravity operated member advances said supplemental carriage relatively to said first-named carriage whereby by movement of said supplemental carriage the tiltable member is operated.
- 15 4. In a charging device, the combination of a carriage, means for advancing and withdrawing same, a supplemental carriage mounted on said first-named carriage and movable relatively with relation thereto, a forwardly tiltable member, bars on said first-named carriage pivotally connected to said member, bars on said supplemental carriage pivotally connected to said member, a bell-crank member on said first-named carriage, connections between said bell-crank member and said supplemental carriage, and a track on which said bell-crank 20 moves, whereby when said bell-crank leaves said track said supplemental carriage is advanced relatively to said first-named carriage whereby by movement of said supplemental carriage the tiltable member is operated.
- 25 5. In a charging device, the combination of a carriage, means for advancing and withdrawing the same, a supplemental carriage mounted on said first-named carriage and movable with relation thereto, a forwardly tiltable member, connections between said first-named carriage and said member, connections between said supplemental carriage and said member, means for advancing said supplemental carriage relatively to said first-named carriage, and a stop for controlling the movement of said supplemental carriage.
- 30 6. In a charging device the combination of a carriage, means for advancing and withdrawing same, a supplemental carriage mounted on said first-named carriage and movable with relation thereto, a forwardly tiltable member, bars on said first-named carriage pivotally connected to said member, a compensating arm on said supplemental carriage, bars connecting said compensating arm with said member by pivotal connections, and means for advancing and withdrawing said supplemental carriage relatively to said first-named carriage whereby by movement of said supplemental carriage the tiltable member is operated.
- 35 7. In a charging device, the combination of a carriage, means for advancing and withdrawing same, a supplemental carriage mounted on said first-named carriage and movable with relation thereto, a forwardly tiltable member, connections between said first-named carriage and said member and between said supplemental carriage and said member, a bell-crank mounted on said first-named carriage, a link connecting said bell-crank with said supplemental carriage, and a track on which said bell-crank travels, whereby when said bell crank leaves said track said supplemental carriage is advanced relatively to said first-named carriage.
- 40 In testimony whereof, I the said JOHN N. CAREY, have hereunto set my hand.
- 45 5. In a charging device, the combination of a carriage, means for advancing and withdrawing the same, a supplemental carriage mounted on said first-named carriage and movable with relation thereto, a forwardly tiltable member, connections between said first-named carriage and said member, connections between said supplemental carriage and said member, means for advancing said supplemental carriage relatively to said first-named carriage, and a stop for controlling the movement of said supplemental carriage.
